UNITED STATES PATENT OFFICE.

ROBERT. F. HALL, OF SCHENECTADY, NEW YORK.

TRUCK FOR RAILROAD ROLLING STOCK.

Application filed November 29, 1922. Serial No. 603,917.

To all whom it may concern:

Be it known that I, ROBERT F. HALL, a citizen of the United States, residing at Schenectady, in the county of Schenectady and State of New York, have invented a certain new and useful Improvement in Trucks for Railroad Rolling Stock, of which improvement the following is a specification.

10 My invention relates to trucks for railroad rolling stock, of the class or type in which lateral resistance devices, of the rocker type, are provided, and is an improvement on that set forth in Letters Patent of the 15 United States No. 1,060,222, granted and issued to W. E. Woodard, under date of April 29, 1913.

The object of my invention is to provide means for ensuring the coincident movement 20 of the laterally moving bolster, during the lateral displacement of the bolster from its normal central position, thereby preventing the relative slipping of said members, which is an objection that is encountered in practice.

25 The improvement claimed is hereinafter fully set forth.

In the accompanying drawings: Figure 1 is a view, half in elevation and half in vertical central transverse section, of a two wheeled locomotive leading truck, embodying my invention, the bolster and rockers being shown in the normal central position which they assume when the locomotive is 35 on a tangent track; Fig 2, a similar view, showing the bolster and rockers displaced laterally when the locomotive is on a curved track; Fig. 3, a view, in elevation, of a double rocker member; Fig. 3^a, a transverse section through the same; Fig. 4, a view, in elevation, and on an enlarged scale, of a rocker and the adjoining portion of a bolster, when in the position shown in Fig. 1; Fig. 5, a similar view of said members, when 45 in the position shown in Fig. 2; and, Fig. 6, a view, showing different positions of the pin in the bolster slot.

50 My invention is herein exemplified as applied in a two wheeled locomotive leading truck of the swing or lateral motion type, in which, as in present practice, a frame, 1, is supported, through the intermediation of springs, 11, on the journal boxes, 4, of an axle, 5, on which the truck wheels, 5^a, are 55 secured. A bolster support, 6, extends from one to the other of the side members of the

truck frame, to which it is rigidly secured at its ends. The weight carried by the truck is primarily applied thereto through a floating or swing bolster, 7, which is provided with a centre plate, 7^a, perforated for the passage of a centre pin. The bolster is supported, with the capacity of relative lateral movement, relatively to the truck frame, on the double curved upper bearing faces of 60 counterpart cam rockers, 9^a, upon each of which it abuts by double upwardly inclined or V shaped bearings, 7^b, formed on its lower side. The cam rockers and bolster bearings are, as in ordinary practice, disposed on opposite sides of the vertical longitudinal and transverse central planes of the truck and the rockers, 9^a, or the pairs on each side of the longitudinal central plane may be connected by being made integral 65 with a body, 9, on which is formed an upwardly extending lug, 9^c, as shown in Figs. 3 and 3^a. The cam rockers are adapted to swing, in one or the other direction, about the axes of segments journals, 9^b, extending, 70 parallel with the longitudinal central plane of the truck, on opposite sides of their bases, and fitting in correspondingly recessed bearings in the bolster support, 6.

In the practice of my invention, I provide 65 means whereby each of the cam rockers, 9^a, is coupled to the bolster, 7, thus ensuring coincident movement of said members, in their lateral displacement, said means being so constructed as to approximately compensate 70 for the difference between the movement of the bolster in a right line, and that of the rocker in a circular arc. To this end, a horizontally extending pin, 9^d, which is fixed, directly or intermediately, to, and 75 therefore partakes of the movement of each rocker, is fitted to engage a slot, 7^d, in the lower portion of the bolster, above said pin. The slot, 7^d, is of substantially triangular 80 form, as clearly shown in Figs. 4, 5 and 6, 100 being narrower at its upper end, and wider at its bottom, thereby providing for the rectilinear and the curvilinear movements, respectively, of the bolster and the rockers, while maintaining the continuous connection 105 of said members, during such movements.

When the two rockers of each pair are connected by an interposed integral body, as shown in Figs. 3 and 3^a, the pin, 9^d, is 110 preferably secured in an upstanding lug, 9^e, on the body, in line axially with the mid-

dle line of the rocker. In cases where separate rockers are applied, one of the pins, 9^a, is fixed in each rocker. The position of the pin in the slot, at different points in the traverse of the rocker, is shown in Fig. 6.

It will be obvious that, if desired, the positions of the pin and slot may be reversed without variation from their operative relation or from the spirit of my invention; the pin may be located on the bolster and the slot on the rocker, and also that while the invention is more particularly desirable in connection with separate rockers, it is equally applicable when two rockers of a pair are formed in an integral casting.

I claim as my invention and desire to secure by Letters Patent:

1. In a railroad truck, the combination of a frame; a bolster, adapted to traverse laterally relatively thereto; a swinging cam rocker, journalled in bearings on the frame, extending transversely to the bolster; and means for positively coupling the bolster

and the rocker, comprising a pin, fixed in one of said members, and a slot, of varying width, formed on the other, in which slot said pin engages.

2. In a railroad truck, the combination of a frame; a bolster, adapted to traverse laterally relatively thereto; a swinging cam rocker, journalled in bearings in the frame, extending transversely to the bolster; and means for positively coupling the bolster and the rocker, comprising a pin, fixed on one of said members, and a slot, of substantially triangular shape, formed on the other, in which slot said pin engages.

3. In a lateral motion railroad truck, a bolster, having double inclined or V-shaped bearings on opposite sides of its base, and slots, of substantially triangular form, below said bearings.

ROBERT F. HALL.
